(57) **CLAIM**

The ornamental design for an apparatus for communications, substantially as shown and described.

DESCRIPTION

FIG. 1 is a perspective view of the apparatus for communications in accordance with the present design;

FIG. 2 is a perspective view of the apparatus for communications in an alternate position from FIG. 1;

FIG. 3 is a rear perspective view of the apparatus for communications shown in FIG. 1;

FIG. 4 is a front view of the apparatus for communications shown in FIG. 1;

FIG. 5 is rear view of the apparatus for communications shown in FIG. 2;

FIG. 6 is a right side view of the apparatus for communications shown in FIG. 2;

FIG. 7 is a left side view of the apparatus for communications shown in FIG. 2;

FIG. 8 is a top view of the apparatus for communications shown in FIG. 1; and,

FIG. 9 is a bottom view of the apparatus for communications shown in FIG. 1.
